(57) **CLAIM**

The ornamental design for a bottle with resilient sleeve and cap, substantially as shown.

DESCRIPTION

FIG. 1 is a perspective view of a bottle with resilient sleeve and a cap, showing our new design;

FIG. 2 is a front view of the bottle with resilient sleeve and the cap;

FIG. 3 is a rear view of the bottle with resilient sleeve and the cap;

FIG. 4 is a right side view of the bottle with resilient sleeve and the cap;

FIG. 5 is a left side view of the bottle with resilient sleeve and the cap;

FIG. 6 is a top view of the bottle with resilient sleeve and the cap; and,

FIG. 7 is a bottom view of the bottle with resilient sleeve and the cap.

The broken line elements in all views are for illustrative and environmental purposes only and form no part of the claimed design.

The resilient sleeve material is an opaque or translucent, pliable polymer material of a dissimilar shade or color with respect to the bottle, and the bottle being composed of glass. A portion of the disclosure of this patent document contains material which is subject to copyright protection. The copyright owner has no objection to the facsimile reproduction by anyone of the patent document or patent disclosure, as it appears in the U.S. Patent and Trademark Office patent file or records, but otherwise reserves all copyright rights whatsoever.
